BLIND RIVET STEM TRIMMER

Everett D. Smith, Lynwood, Calif., assignor to Northrop Corporation, Beverly Hills, Calif., a corporation of California

Filed Mar. 3, 1959, Ser. No. 796,878
1 Claim. (Cl. 30—167)

This invention relates to cutting tools and more particularly to a tool for removing the extending shank portion of a blind rivet or like fastener.

The performance of tools, for example conventional metal saws, diagonal cutters and the like utilized in the removal of the extending or projecting shank portion of blind rivets and like fasteners, also the results forthcoming from an operation of this type, are generally unsatisfactory. An operation, performed with currently available tools of the above type, may result in the loosening of rivets relative to the members which they secure; the rivets themselves may be damaged or the surface surrounding the rivets may be marred.

The cutting or trimming tool as disclosed herein includes an adapter mounted on a fluid type rotary motor; the adapter, however, may be used with any type rotary motor. Specifically the instant tool is utilized to remove the projecting shank portions of blind rivets whereby a substantially flush relationship is provided between a rivet and a plane surface of structure surrounding the rivet.

An object of the present invention is to provide a cutting tool for removing the projecting shank portions of blind rivets or like fasteners in substantially flush relation with respect to an outer plane surface of structure secured by the rivets.

Another object is to provide a cutting tool for removing the shank portions of blind rivets and like fasteners which does not damage the rivets or mar a surrounding surface during the operation.

Another object is to provide a cutting tool for removing the projecting shank portions of blind rivets which is of a compact light weight construction rendering the tool extremely mobile.

Although the characteristic features of the present invention are particularly pointed out in the appended claim, the invention itself, also the manner in which it may be carried out, will be better understood by referring to the following description taken in connection with the accompanying drawings forming a part of this application and in which:

FIGURE 1 is a perspective view of one embodiment of a cutting tool as disclosed herein.

FIGURES 2 and 3 are side and plan views, respectively, of an adapter usable with the motor shown in FIGURE 1.

Referring to the drawings in FIGURE 1 the numeral 11 identifies a preferred embodiment of the cutting tool as disclosed herein. The tool 11 includes a fluid type rotary motor 12 and a fitting or adapter 14.

The motor 12 may be of any type capable of imparting high speed rotary motion to its output member. The fluid type rotary motor shown in FIGURE 1 includes a body portion 16, an output member 17, trigger means 18 and means 19 located at the aft end of the body portion adapted to receive a hose (not shown) through which pressurized air is supplied to the motor 12.

Mounted on the outer end of the output member 17 is a circular disk-like member 21 having teeth formed in and defining the periphery of the disk. As mounted on the member 17 the outer face of the disk 21 extends beyond or at least has a flush relation with the outer end of the member 17. The member 17 has a right angle

2

relation with respect to the axis of the body portion 12; this relation provides an advantage which will become apparent as the disclosure progresses.

In the embodiment shown in FIGURE 1 the adapter 14 includes a base portion 22 of strap-like configuration and an upstanding portion 23 of cylindrical configuration. The forward end of the base portion is enlarged as indicated by the numeral 24 and has a circular aperture 26 formed therein. The aft end portion 27 of the base portion has a right angle relation with respect to the portion 24. Provided at the extreme end of the portion 27 is an aperture (not shown) which, together with portion 23, provides means for securing the adapter 14 to the motor 12.

10 The upstanding portion 23 is secured to the portion 24 in concentric relation with respect to the aperture 26. The portion 23 is cut away to provide an observation port 28 through which a rivet cutting operation may be observed. The solid part of the portion 23, that is the portion above the port 28, is longitudinally slit as indicated at 29 to allow expansion and contraction of the portion 23. Ears 31 are provided adjacent each side of the slit 29 which together with a screw member provide means for closing the upper portion of the portion 23.

15 20 25 The adapter 14 is rigidly secured to the motor 12 by means of the contracting feature of the portion 23 and the aperture provided in the portion 27 substantially as shown in FIGURE 1. The aft end of the body portion 16 passes through the aperture in the portion 27 and is maintained in this position by a nut 32; the upstanding portion 23 is attached to the motor 12 by means of the ears 31 and associated screw member.

20 25 30 35 With the adapter 14 assembled on the motor 12 in the above manner it will be seen that the cutter 21 is located in the aperture 26 so that a substantially coplanar relation is present respectively between the upper and lower faces of the portion 24 and cutter 21. In this respect the lower surfaces of the cutter and portion 24 are located in a common plane regardless of the exact relationship of corresponding upper surfaces. Further, it will be seen that the axis of the output member 17 has a normal relation with respect to the lower surface of the portion 24. The diameter of the aperture 26 is such as to provide predetermined clearance therebetween and the cutter 21.

35 40 45 50 Formed in the portion 24 is a radial slot 33 extending between the aperture 26 and the edge of the portion 24. The slot 33 is of sufficient width to receive the shank portion of a blind rivet to be cut and is located so that the center line thereof substantially coincides with the longitudinal center line of the adapter 14. The slot 33 may be located elsewhere in the portion 24, however, experience has shown that the above location is the most satisfactory.

55 60 65 70 Mounted on one side of the slot 33 by means of a screw or the like is an L-shaped block 34. The purpose of this block is to support the shank of a rivet until the latter is completely cut or parted from the remainder of the rivet. The upright portion of the block 34 extends a predetermined distance beyond the perimeter of the aperture 26 and in so doing provides better support of a rivet shank being cut and also minimizes the possibility of a rivet shank from being drawn into the clearance space provided between the cutter and portion 24. The working face of the block 34 has a flush relationship with one side of the slot 33, in this instance the near side of the slot 33 assuming that the cutter rotates in a clockwise direction as viewed from above as shown in FIGURE 1.

70 The embodiment of the adapter 36 as shown in FIGURES 2 and 3 is quite similar to the adapter of FIGURE

1. The strap-like base portion 22 of FIGURE 1 is replaced by a plate-like base portion 37 in FIGURES 2 and 3. The upstanding portion 38 is similar to the portion 23 of FIGURE 1, however, a pair of diametrically opposed observation ports are provided in the portion 38. Otherwise the adapter 36 is similar in construction to the adapter 14 of FIGURE 1. However, the adapter 36 is secured in position on the motor 12 by the upstanding portion 38 only. When assembled on the motor 12 the side surfaces of the plate 37, particularly the lower surface of the plate 37, are normal to the axis of the output member 17 and the lower surfaces of the cutter and the plate portion 37 lie in a common plane.

In operation the lower surface of the portion 24 (FIGURE 1) or the lower surface of the portion 37 (FIGURE 2 and 3) rests on a plane surface of structure through which the shank portion of a blind rivet extends. With the lower surface of the portion 24 or of the portion 37 in firm contact with the surface of the structure through which a blind rivet extends, the extending portion of the rivet is fed into the slot 33 and urged into contact with the cutter 21. The cutter 21, having a parallel relation with respect to the aforementioned plane surface of the structure and rotating at a high rate of speed, quickly and efficiently parts the extending shank portion of the rivet substantially flush with plane surface of the structure without marring or defacing the latter in any respect.

In view of the above description it will be seen that a cutting tool capable of carrying out the various objects of the invention is disclosed. By using a motor of the type shown in FIGURE 1, that is a motor in which the output member thereof has a right angle relation with respect to the body portion of the motor, a well balanced tool which is easy to handle and manipulate is provided.

While in order to comply with the statute, the invention has been described in language more or less specific as to structural features, it is to be understood that the invention is not limited to the specific features shown,

but that the means and construction herein disclosed comprise a preferred form of putting the invention into effect, and the invention is therefore claimed in any of its forms or modifications within the legitimate and valid scope of the appended claim.

What is claimed is:

A cutting tool including a rotary motor having an output member and an adapter; the relation of said motor and output member being further characterized in that the axes of said output member has a normal relation with respect to the axis of rotation of said motor; a disk-like cutting element mounted on the outer end and rotating with said output member; said adapter being constructed of strap-like material including base and securing portions; said base portion having outer edges and a circular aperture formed therein; an upstanding attaching member secured to said base portion; said adapter being mounted on said motor and being further characterized in that said securing portion and upstanding member are respectively attached to the opposite ends of said motor so that said base portion has a parallel relation with respect to the axes of rotation of said motor and the side surfaces of said cutting element have a coplanar relation with respect to the side surfaces of said base portion; said base portion having a radial slot formed therein extending between said aperture and an outer edge thereof; and a plate-like stop member secured to said base portion with one side thereof aligned with an edge of said slot and an end portion of said stop member extending a predetermined distance inboard of the perimeter of said aperture.
